UNITED STATES PATENT OFFICE.

WILLIAM F. HELMOND, OF HARTFORD, CONNECTICUT, ASSIGNOR TO UNDERWOOD TYPE-WRITER COMPANY, OF NEW YORK, N. Y., A CORPORATION OF NEW JERSEY.

TYPE-WRITING MACHINE.

No. 919,012.

Specification of Letters Patent.

Patented April 20, 1909.

Application filed October 17, 1907. Serial No. 397,770.

To all whom it may concern:

Be it known that I, WILLIAM F. HELMOND, a citizen of the United States, residing in Hartford, in the county of Hartford and State of Connecticut, have invented certain new and useful Improvements in Type-Writing Machines, of which the following is a specification.

This invention relates to the paper feeding devices of typewriting machines, and particularly to means for controlling the pressure rolls that run upon the usual cylindrical platen.

The object of the invention is to provide simplified, inexpensive and improved means for releasing the rolls, and also for holding them released or locked away from the platen during the introduction and adjustment of the paper sheets.

In the accompanying drawings, Figure 1 is a front view of a platen frame of an Underwood front-strike writing machine. Fig. 2 is a perspective view illustrating the mounting of the rolls and releasable springs therefor. Fig. 3 is an end view of the paper guiding devices, showing the pressure rolls released and locked away from the platen. Fig. 4 is a view similar to Fig. 3, but showing the parts in normal positions.

In said machine the types usually strike upon the front side of a platen 1, which is revolubly mounted by means of an axle 2 in the ends 3 of a platen frame, said ends rigidly connected by a rod 4. Sets of front and rear pressure rolls 5, 6, are carried upon shafts 7, 8, said shafts resting in cradles or yokes 9, each of said shafts or holding devices comprising a U-shaped yoke portion, and arms 10, 11, extending upwardly and rearwardly therefrom and having open bearings 12, 13 to receive the roll shafts and permit detachment thereof.

Springs 14, 15, extend in opposite directions from a bracket 16, the latter secured on said rod 4. Said springs are adjustably held by means of screws 17, 18 against the inner ends 19, 20 of levers which are pivoted at 21, 22 upon brackets 23, 24 also fixed upon said rod 4 and serving as guides for the up and down movements of the yokes 9. Said springs normally press the yokes up, the pressure being independently regulated by the screws 17, 18.

By depressing a release-key 25 provided upon a lever 26 pivoted at 27 upon the platen

frame, a link 28 connected to an arm 29 of said lever pulls up a crank 30 provided upon a rock shaft 31 having means to release said springs 14, 15. Said rock shaft is mounted in brackets 32, depending from said rod 4, 60 and carries collars 33, 34, each having an inclined or beveled cam-face 35, 36, said cam faces adapted to engage the opposite edge 37, 38 of said levers 19, 20.

By depressing the key 25, the shaft 31 is 65 rocked to swing both lever arms 37, 38 upwardly to the position indicated in dotted lines, Fig. 1, whereby both springs 14, 15 are depressed, as indicated in dotted lines, and the yokes 9 permitted to drop to release the 70 rolls, as at Fig. 3. It will be seen that the cams 35, 36 are oppositely disposed, the same being true as to the levers and as to the springs, thus enabling the latter to be fulcrumed together, or close to each other 75 about midway between the yokes 9, which is an advantage and conduces to simplicity and reliability as well as producing an inexpensive construction and permitting easy adjustment of either spring. 80

Each of the cam faces, it will be perceived, is of such form as to lock the lever in the dotted line position, so that by depressing the key 25 the lever arms are held down, there being no action on the part of the 85 springs to raise the same. Thus the operator may freely adjust the sheets, and may thereafter raise the key 25 to restore the rolls to the platen as at Fig. 4.

Having thus described my invention, I claim:

1. In a typewriting machine, the combination with a platen and a platen frame, of a pressure roll, a spring, a yoke caused by said spring to press the roll against the platen, a key-operated rock shaft having a cam thereon, and a lever pivoted upon the platen frame and operated by said cam and bearing against said spring to release the roll. 95

2. In a typewriting machine, the combination with a revoluble platen and a platen frame, of rolls running upon the platen, a plurality of springs, yokes caused by said springs to press said rolls against the platen, a rock shaft having cams thereon, and levers pivoted on the platen frame and operated by said cams and engaging said springs to release the same from said rolls. 105

3. In a typewriting machine, the combination with a revoluble platen, a platen frame, 11

and sets of rolls mounted to run upon the platen, of shafts for said rolls, yokes to hold said shafts, a bracket upon the platen frame between said yokes, springs extending in opposite directions from said bracket to engage said yokes, and key-operating means bearing upon said springs to release the yokes.

4. In a typewriting machine, the combination with a revoluble platen and a platen frame, of sets of rolls mounted to run upon the platen, shafts for said rolls, yokes to hold said shafts, a bracket on said platen frame, springs extending in opposite directions from said bracket to engage said yokes, and key-operated means bearing upon said springs to release the yokes; said releasing means including a rock shaft and levers operated thereby to engage the springs, said levers pivoted on the platen frame.

5. In a typewriting machine, the combination with a revoluble platen and a platen frame, of sets of rolls mounted to run upon the platen, shafts for said rolls, yokes to hold said shafts, a bracket on said platen frame, springs extending in opposite directions from said bracket to engage said yokes, and key-operated means bearing upon said springs to release the yokes; said releasing means including a rock shaft and levers operated thereby to engage the springs, said levers pivoted on the platen frame, and said rock

shaft having oppositely disposed cams to engage said levers.

6. In a typewriting machine, the combination with a revoluble platen and rolls mounted to run thereon, of springs to press the rolls against the platen, a key-operated rock shaft, beveled cams mounted on said rock shaft, and levers extending from said cams to said springs to release the same from said rolls; said cams being formed to lock the springs away from the rolls.

7. In a typewriting machine, the combination with a rotating platen, of a set of pressure rolls, springs to press the rolls against the platen, shafts for supporting the rolls, said shafts held by movable yokes, a rock shaft held by brackets on a rod attached to the machine; a key for operating said rock shaft, cams mounted on said rock shaft, and so formed that they lock the said springs away from the yoke-supported rolls, thus releasing the pressure between the platen and rolls; and levers pivoted between their ends on brackets, said levers bearing on the face of the said cam on one side, and on the other bearing against said springs.

WILLIAM F. HELMOND.
